Specification of Letters Patent. Patented Apr. 27, 1915.

Application filed October 1, 1914. Serial No. 364,415.

To all whom it may concern:

Be it known that we, MARK R. COLBY, a citizen of the United States, residing therein at the city of Portland, in the county of Multnomah and State of Oregon, and JAMES STEWART, a subject of Great Britain, residing at the city of Cleveland, in the county of Cuyahoga and State of Ohio, have invented a new and useful Improvement in Hoisting and Conveying Machines, of which we hereby declare the following to be a full, clear, and exact description, reference being made therein to drawings accompanying and made a part of the specification, where- in the same mechanical parts are designated by the same numerals in each instance.

The invention belongs generally to the class of hoisting and conveying apparatus designed to be suspended from or connected to a trolley which is movably mounted on an overhead trackway, in order to thereby grapple gross loads, like lumber, leather or cotton, which are prepared, for the most part, in piles, packages or bales, of convenient size and dimensions for the process and carry the same to given points for deposit. This type of apparatus has its most extensive field of usefulness, perhaps, in connection with the handling of lumber on a large scale at mills, mill-yards, transfer and storage places, and the illustration of the improvement in question for the purpose of this application, is accordingly of that improvement as applied to operations in said special department of the art to which it relates. As thus applied, the machine, as a whole, is characterized by an overhead trackway, generally in the form of an I-beam, between the terminals and above the area or space to be served, a man-trolley, duly mounted thereon, and lumber-grappling and hoisting mechanism operatively connected thereto. As commonly made this last named feature comprises a hoisting-head of rectangular form, horizontally suspended from its ends, by ropes, to corresponding winding drums on the trolley-frame, and a rectangular frame rotatably hung from this head, and provided at each corner, with downwardly extending hook-arms by which the grapple is made. Said hook-arms are sometimes rigidly connected to said frame at

their upper ends with grappling-hooks pivoted to their lower ends, or, being integrally hooked at said ends, are themselves pivoted to the frame at their upper ends. In either form, said arms, and their hook movements, are always in the same vertical plane with the sides of the frame from which they depend, and, in consequence, although the hook-arms, or the hooks themselves, may be retracted so as to avoid the usual skids or cross-pieces upon which the package rests, they nevertheless will remain normal, and with but slight clearance with respect to the same at all stages. There is, accordingly, a resultant liability that the arms will contact with the top of the load, and require repeated operations before such position is attained. The closing and locking of the hooks too, and other important operative movements in prevailing machines, are not entirely controlled from the cab by positive and simple mechanical means, but either wholly or in part, are brought about by manipulation. Similarly, the turning of said frame, with relation to the trolley or tramway above, which, in good practice, must be promptly and surely made, in order to properly spot the load to be grappled, so as to avoid obstacles or conform to structural conditions during its conveyance, or when laying the load down on car, pile or platform at the terminal, is dependent for the most part either upon men outside the machine, or upon the special activities of the general operator in reaching out from his cab, from time to time, with a hook, and engaging and drawing the swinging load around to the desired angle.

Realizing the need of a unitary machine of the kind in question, which will adequately take care of the movements and conditions referred to, we have devised coördinating parts and features for the same which we will now proceed to more particularly set forth and describe.

In the drawings Figure 1 is a side elevation of a machine containing said improvements. Fig. 2 is a plan of the same with the trolley tracks thereof removed. Fig. 3 is a plan of the hoisting-head feature of the machine. Fig. 4 is a plan of a rectangular grapple-frame and Fig. 5 is a transverse

vertical sectional view of the machine on the lines 1, 1, of Fig. 1, in the direction of the arrow.

Referring to the drawings 1 indicates an overhead tramway, in this case, preferably of the I-beam type. Movably mounted thereon, by its wheels, 2, is a trolley 3, from which hangs an operator's cab 4. Winding drums 5 are located transversely of the trolley with cables 6, 6, and 7, 7, thereon. These, respectively, extend to and around opposing pairs of parallelly arranged sheaves 8, 8, and 9, 9, on the trolley, downwardly to and around corresponding pairs of sheaves 10, 10, and 11, 11, in the opposite ends of a hoisting-head 12, and thence, upwardly, to anchorages 13, on the trolley above. The hoisting-head 12 is a rectangular framework, with parallel cross-beams 14, midway of the same, upon which is mounted a plate 15 having a central opening 16. Two sheaves 10, 10 and 11, 11 are arranged in line, one with the other, at each end of the head, in order that said head may be hung thereby from the trolley at four points.

A lower rectangular frame 18, is rotatably connected to the head 12, by a circular casting composed of upper and lower ring parts 19 and 20; adapted to surround an inner ring 21 in such position to overhang and correspond with annular ball-bearing raceways on said inner ring indicated at 22. The latter ring is fastened to and beneath the cross-beams 14 in the hoisting head, and said component parts 19 and 20, of said casting, when assembled in their denoted places around the same, are duly secured in such relation to the frame 18, by bolting or otherwise. At a predetermined point on the hoisting head 12, within housings 48, is located a spring-bolt 49, which normally extends below said head and is retractable against its spring 50. Sockets 51 are arranged on the frame beneath, at radial distances from the center of rotation of the frame corresponding with the distance of said bolt therefrom, to engage said bolt as the frame revolves, and thereby stop the rotation and lock the parts firmly together. In order to unlock said parts and permit further rotation of said frame, a pulling-rope 52 passes from the top of said bolt over a guide pulley 53 to and around a second pulley 54 on said frame below the hollow journal 43, thence through said journal upwardly around a sheave 55 on the top of the journal to a sheave 56 on the side of the trolley and backwardly around a pulley 57 at the rear where it extends to a point in the cab below conveniently within the cab-man's reach. In the device shown in the drawings, downwardly extending hook-arms 23 are, severally, pivotally connected to said frame at each corner exteriorly of the same, by hinges or pivots denoted by 24, 24. These

arms are straight angle-pieces which terminate in oppositely disposed hooks 25, at the lower ends thereof. The hooks themselves are shown as normally related to the arms proper 23 and integral therewith. The pivotal connections 24 of said arms to the sides of the frame are such that, when free to move around their pivots, the arms will fall into and assume vertical positions, in the same plane with each other on the respective sides of the frame, but may be retracted toward each other around said connections when occasion requires. To effect these necessary grappling movements the two hook-arms 23 at each side of said frame are united together, from intermediate points of their lengths, by lever-bars or links 26 which have their outer ends pivoted to the hook-bars as indicated at 27 and their inner ends jointedly connected together at the junction point 76. These lever-bars should be of the same length, which should also be such that they will be in one and the same straight line when the arms to which they are connected occupy their normally depending positions with respect to said head 12; said lever-bars should have such weight and relative dimensions, that, when free to descend by force of gravity around their pivots, their leverage will overcome the inertia of said arms, and withdraw the same from their normal position, backwardly around their said pivotal connections, to any degree necessary to clear the skids or crosspieces beneath a load during the lowering stage of the grappling movement. In order to afford a wider margin than usual to clear the load itself during said movement, we relate the pivot connections of said hook-arms 23 to said frame diagonally with respect to the same, so that such connections, operatively considered, shall lie in the same horizontal plane with each other, and at a given or predetermined angle with a transverse vertical plane passing through the frame itself. By reason of the angular relation just described, a corresponding and secondary motion is afforded the arms themselves when retracted toward each other, which insures a wider clearance from the load during the grappling operation, and, at the same time, by their slanting attitude, the arms will serve to effectively guide the grappler as an hole, to its operative relation to the load to be hoisted.

To enable the operator to effect the turning movements of the grappling-frame hereinbefore referred to, mechanically from his customary place in the cab, a horizontal sheave 31, commonly known as the bull-wheel, is horizontally mounted upon a hollow upright journal 43 securely fastened to and beneath a pair of cross-beams or members 33, in the forward part of the trolley 3. An actuating-rope 34 is frictionally wrapped

around this sheave, and its ends carried laterally therefrom to and around sheaves 35 and 36 on the trolley, and backwardly and oppositely around or fastened to a hand-drum 37 near the cab. This drum is revolvable, in both directions, by means of a crank-wheel 38 and shaft 39, as indicated. Through the bull-wheel 31, near its rim, is an annular series of perpendicular holes 40, and, at diametrical points on said lower frame 18, in line with the path of rotation of said holes, are two upright locking-bolts 41. Said bolts are of suitable shape and dimensions to reach and loosely fit into and engage said holes when the grappling and hoisting mechanism to which they pertain is raised into close proximity with the trolley beneath the bull-wheel 31. It will be evident that when said bull-wheel and grappling-frame are thus interlocked, the grappling-frame 18 and its depending load, by a simple manipulation of the hand-drum 37, may be correspondingly turned about its swivel connection to the head 12, to a distance of ninety degrees altogether, (see full-line arcs in Fig. 3) and firmly held in any position so gained, while the trolley with its suspended load is traversed along the trackway.

To give a like control from the cab, of the grappling movement of the hook-arms 23, from their withdrawn position toward and beneath the skids on which the waiting loads rest, a rope 42, fastened to a retriever 17, in the cab, extends forwardly to and around a sheave 44, on the trolley-frame opposite said bull-wheel 31, thence, transversely of said frame, to and around a sheave 45 thereon, immediately above the hollow upright journal 43; thence, downwardly, through said journal, and the central openings 16, in the hoisting head 12, and in the rings 19 and 20 in the frame beneath, when it is bifurcated, and its component branches or parts are led, respectively, to the right and left, in operative bearings with guide sheaves 46 and 47, in alinement with each other on the under side of said frame, to the junction points of the lever-bars or links 26. By this means said lever-bars may be actuated upwardly by the operator in the cab, and the hook-arms themselves thereby moved, in unison with each other into their several grappling relations designed.

The diagonal pivotal connections 24, of the hook-arms 23 to the lower frame 18, which is a special form and feature of the improvement claimed, may be brought about in any suitable manner. In the form illustrated herein, it will be sufficiently apparent that the hook-arms themselves are angle-bars with their lower ends turned into the hooks proper 25, at normal relations with the arms. The latter, however, are affixed to a hinge-box or piece 59 at their top which is fastened to the frame at the angle desired.

The pivot in said box, indicated by 24, is, itself, in consequence, at a corresponding angle. By this arrangement the arms will fall away from the frame, when free so to do, at the same angle as the pivot and may be brought up or returned to their normal perpendicular position with the upper face of the hooks in full bearing beneath the skids under the load to be raised.

Having thus described our said invention as concretely applied to a practical machine, what we claim and wish to protect by Letters-Patent is:—

1. In a hoisting and conveying machine, the combination with an overhead trolley 89 provided with a horizontal sheave mounted on an axle and containing an annular series of grappling engagement holes, a lifting-head connected with the trolley, a grapple having a swivel connection with said head, 35 a sheave-engaging bolt on said grapple in line with the path of rotation of said holes and extending upwardly through said head, suitable means for raising and lowering said head and grapple with relation to the trolley, and means for rotating said sheave, substantially as shown and described.

2. In a hoisting and conveying machine, the combination, with an overhead trolley, of a hoisting-drum, a lifting head, having 95 an open space therein, connected with said drum by cables from a plurality of diametric points on the same, and provided with a central bearing-ring, a grapple comprising a frame with a bearing-ring, forming with 100 the other ring a swivel connection between said head and grapple, hooks pivotally connected to said frame, and a sheave on said trolley, having annularly arranged holes 105 therein, said sheave being horizontally mounted on the trolley; an upright locking-bolt on said grapple in line with the path of rotation of said holes and extending through said open space, together with suitable means for rotating said horizontal sheave 110 around its said axle, substantially as shown and described.

3. In a hoisting and conveying machine, the combination, with an overhead trolley, of a hoisting-drum, a lifting head, having 115 an open space therein, connected with said drum by cables from a plurality of diametric points on the same, and provided with a central bearing-ring, a grapple comprising a frame with a bearing-ring, forming with 120 the other ring a swivel connection between said head and grapple, hooks pivotally connected to said frame; a sheave on said trolley, having annularly arranged holes therein, said sheave being horizontally mounted 125 on the trolley, a hollow axle in vertical alinement with said rings; an upright locking-bolt on said grapple in line with the path of rotation of said holes and extending through said open space, a hook-operating 130

connection passing through said rings and hollow axle, together with suitable means for rotating said horizontal sheave around its said axle, substantially as shown and described.

4. In a hoisting and conveying machine, the combination, with an overhead trolley, of a hoisting-drum, a lifting head having an open space therein, connected with said drum by cables from a plurality of diametric points on the same, a grapple-frame, having a swivel connection with said head, and hook-arms pivotally connected thereto on lines in a horizontal plane and at predetermined angles with respect to a transverse vertical plane through said frame, a sheave on said trolley, having annularly arranged

holes therein, said sheave being horizontally mounted on the trolley, an upright locking-bolt on the grapple-frame in line with the path of rotation of the holes and extending through said open space, together with suitable means for rotating said horizontal sheaves, substantially as shown and described.
